ATTORNEY

UNITED STATES PATENT OFFICE.

JOHN T. DAVIS, OF ALAMEDA, CALIFORNIA, ASSIGNOR TO DAVIS TOPPING COMPANY, OF SAN FRANCISCO, CALIFORNIA, A CORPORATION OF ARIZONA.

EVAPORATING AND DISTILLING APPARATUS.

1,103,946.

Specification of Letters Patent.

Patented July 21, 1914.

Application filed April 21, 1913, Serial No. 762,663. Renewed June 13, 1914. Serial No. 845,009.

To all whom it may concern:

Be it known that I, JOHN T. DAVIS, a citizen of the United States, residing at Alameda, in the county of Alameda and State 5 of California, have invented new and useful Improvements in Evaporating and Distilling Apparatus, of which the following is a specification.

This invention is to provide an improved 10 and effective apparatus for the distillation of oil and other liquids which comprise constituents of different gravities and vaporizable at different temperatures.

In the accompanying drawing, Figure 1 15 is a vertical section of my improved apparatus; Fig. 2 is a cross section on the line 2—2 of Fig. 1; Fig. 3 is an enlarged vertical section of a portion thereof; Fig. 4 is a side view of a lower expansible ring.

20 Referring to the drawing, 1 indicates a cylindrical casing of a receptacle, which is divided into an oil chamber 2 at the top, and vaporizing chambers 3, 4 and 5. Oil is supplied to said oil chamber by a pipe 6, leading 25 into the top of said cylindrical receptacle, and vapor is drawn from said vaporizing chambers by means of pipes 7, 8 and 9, which lead to condensers, not shown. Extending coaxially through said receptacle 30 are inner and outer cylindrical tubes 10, 11, forming therebetween an annular steam chamber 12, closed at the top and bottom by annular plates 13, 14, pressed against the ends of said side tubes 10, 11, by cap nuts 15 35 screwed on the ends of bolts 16 passing through said plates. A steam supply pipe 17 connects with the top of a vertical coil of pipe 18 within the inner tube 10, the other end of said coil being connected, as shown at 40 19, with the top of the annular steam chamber 12, an outlet pipe 21 being connected with the bottom of said steam chamber. Secured upon the upper annular plate 13, and surrounding the upper portion of the coil of 45 pipe 18, is a flue 22, through which products of combustion from a burner 23 at the bottom of the tube 10 can escape after passing up around the coils of pipe 18.

The bottom of the oil chamber 2 is formed 50 by a transverse partition 24, which extends from the cylindrical casing 1 to within a short distance of the outer tube 11. Upon the inner portion of said partition rests an expansible spring ring 26, which is pressed 55 inwardly against its resilient force by screws

27, screwed through the casing, the inner ends of which abut against the said ring. By screwing said screws inwardly, more or less, the diameter of the ring can be decreased as desired, and thus can be varied. 60 the space between said ring and the outer tube 11. This variation in the size of the space surrounding the tube or cylinder 11 is most desirable in order to adjust the space for oils of different gravities. In other 65 words, when operating with a heavy oil the space should be increased by opening the ring, and the space should be decreased by closing in the ring when operating with a light oil. The ring is so constructed that 70 when not under pressure it is at its maximum size, so that pressure of the screws on the sides thereof will compress the ring, moving the overlapping portions thereof over each other. This is effected without 75 difficulty because of the very small change in diameter that has to be made.

The transverse partitions 28 of the vaporizing chambers 3, 4, 5, are depressed in their central portion, and, like the partition 24, 80 extend from the cylindrical wall 1 of the receptacle to within a short distance of the outer tube. Upon the inner portions of said partitions are expansible spring rings 29, 85 adjusted by screws 31, in like manner as the ring 26, to vary the distance between said rings and the outer tube. With the bottom of the receptacle connects a pipe 32 for conveying away the residuum of the oil, and upon said bottom is a low wall 33 surrounding the outer tube 11, and from said bottom 90 within said wall leads a tube 34.

The following is the operation of the apparatus: Steam is admitted by the pipe 17 into the coil of pipe 18 where it is superheated by the products of combustion from the burner 23. Oil supplied by the pipe 6 to the chamber 2 escapes by the narrow circular opening between the outer tube 11 and the ring 26, and flows down in a thin film 100 around the outer tube through the upper vaporizing chamber 3, where the lighter constituents of the oil are vaporized, and escape by the pipes 7, and are conducted thereby to a condenser. The remaining film of oil, as 105 well as that condensed in the vaporizing chamber 3 and flowing to the bottom of the upper partition 28 escapes between the outer tube and the ring 29 and flows into the second vaporizing chamber, where, by the heat 110

2
transmitted through the outer tube 11 from the steam in the annular chamber, the lighter remaining constituents of the oil are vaporized, the vapor being conducted away by the 5 pipe 8 to a condenser. Precisely the same operation occurs in the lowermost vaporizing chamber. The oil condensed in the lowermost vaporizing chamber flows off the pipe 32 to be redistilled. In the lowermost 10 vaporizing chamber only the asphaltic residuum of the oil is left, which, comprised within the wall 33, is conducted away by the pipe 34.

By superheating the steam before delivering it to the annular steam chamber I am 15 enabled to obtain a high but easily limited degree of heat, and to utilize this heat for separating the volatile constituents of the oil. In this way I avoid the direct application of the heat of combustion to the surfaces over which the oil and asphaltic residuum flow. It is found that, if said asphaltic residuum is permitted to flow over plates which are heated directly by the products of 20 combustion, the asphaltum is changed in character and approximates anthracine. It is the object of my invention to avoid this change and to retain the asphaltum in the character in which petroleum forms an ingredient of the asphaltum, this being the 25 most valuable ingredient of natural asphaltum since it gives to it its elastic property. In the recovery of asphaltum from oil, the oil has heretofore been treated so that the 30 asphaltum loses this valuable ingredient. By 35 my invention, this ingredient is retained.

I claim:

1. In an apparatus for distilling petroleum or the like, the combination with a 40 chamber, of means for supplying steam to the interior of the chamber, means for feeding the petroleum or the like in a thin film over one surface of the chamber, means for applying heat to the opposed surface of the 45 chamber, whereby the steam is interposed between the film of oil and the applied heat, a casing inclosing the oil carrying surface of the chamber, partitions carried by the casing and extending closely adjacent to the 50 oil carrying surface to divide the casing into compartments, and means for separately removing the distillates from each compartment.

2. In an apparatus for distilling petroleum and the like the combination with two 55 vertical substantially concentric cylinders having an annular steam space between them, of means for feeding steam into said

space, means for applying fire heat to one surface of the annulus, means for supplying 60 oil in a thin vertically flowing film on the other surface of the annulus, vertically superposed compartments whose floors are slightly spaced from the film-carrying surface, and means for separately removing the 65 distillates from each compartment.

3. In an apparatus for distilling petroleum or the like, the combination with a casing, of a vertically arranged cylinder located within the casing, means for feeding 70 the petroleum or the like in a thin film over the outer surface of the cylinder, partitions carried by the casing and extending closely adjacent to and surrounding the outer surface of the cylinder to divide the casing into 75 compartments, a second cylinder located within the first mentioned cylinder and spaced therefrom, means for supplying steam to the space between the cylinders, means for supplying heat to the interior of 80 the second mentioned cylinder, and means for separately removing the distillates from each compartment.

4. In an apparatus for distilling petroleum or the like, the combination with a casing, of a vertically arranged cylinder located within the casing, means for supplying heat to the interior of the casing, a partition carried by the casing and extending closely adjacent to and surrounding the cylinder to divide the casing into compartments, adjustable means carried by the partition to vary the space between the inner 85 edge of the partition and the cylinder, and means for separately removing the distillates from each compartment.

5. In an apparatus for distilling petroleum or the like, the combination with a casing, of a vertically arranged cylinder located within the casing, means for supplying 100 heat to the interior of the casing, a partition carried by the casing and extending closely adjacent to and surrounding the cylinder to divide the casing into compartments, a split ring supported on the partition and surrounding the cylinder, means for varying the diameter of the ring, and means for 105 separately removing the distillates from each compartment.

In testimony whereof I have hereunto set 110 my hand in the presence of two subscribing witnesses.

JOHN T. DAVIS.
